UNITED STATES PATENT OFFICE

HUBERT K. KRANTZ, OF ROCKVILLE CENTER, NEW YORK, ASSIGNOR TO WESTINGHOUSE ELECTRIC & MANUFACTURING COMPANY, A CORPORATION OF PENNSYLVANIA

ELECTRICAL SWITCH

Original application filed August 8, 1922, Serial No. 580,409. Divided and this application filed May 18, 1926. Serial No. 109,822.

My invention relates to electric switches and particularly to those of the type wherein more than one switching operation is employed for starting motors.

5 My invention is particularly applicable for use in connection with small motors, such as are employed for driving household appliances and it has for one of its objects the provision of a compact structure embodying switches for controlling the circuits through the starting and running windings of a motor, together with means for automatically interrupting the circuit through the motor in case a short circuit or an over-load occurs—either during the starting of the motor or when such motor is operating under running conditions.

Another object of my invention is the provision of means whereby the switch that 20 controls the circuit through the starting winding will be automatically moved to open position after sufficient time has elapsed to enable the motor to attain its normal running speed.

25 Another object of my invention is the provision of a simplified form of operating mechanism whereby but a single handle is necessary in order to manually effect the operation of both switches.

30 A further object of my invention is the provision of means whereby the position of the operating handle when at rest indicates the position occupied by the running switch.

35 Another object of my invention is the provision of an improved form of trip-free mechanism whereby the switch may be automatically disengaged from the closing mechanism, when the switch reaches its 40 closed position in order to insure that the switch will not be held closed against an overload on the circuit.

Still another object of my invention is to simplify and improve generally the construction and operation of circuit controlling 45 devices of the character above referred to.

As shown in the accompanying drawings,

Figure 1 is a plan view of a switch embodying my invention, the cover and the handle 50 being removed,

Fig. 2 is a view, partially in side elevation and partially in section, of the switch,

Fig. 3 is a detail view of the stationary contact members,

Fig. 4 is a plan view of the cover plate, 55

Figs. 5 and 6 are side elevational and plan views, respectively, of the handle bracket,

Figs. 7 and 8 are plan and side elevational views, respectively, of the bracket which carries the movable contact members of the 60 running switch,

Figs. 9 and 10 are plan and side elevational views, respectively, of the bracket which carries the movable contact members of the 65 starting switch,

Figs. 11 and 12 are plan and side elevational views, respectively, of the lever for locking the running switch,

Figs. 13 and 14 are detail views of the upper and lower bearings respectively for the 70 movable contact bracket members,

Fig. 15 is a detail view of one of the pins employed for effecting a connection between the handle bracket and the moving parts of the switch, 75

Fig. 16 is a plan view showing the positions occupied by certain of the moving parts at one stage of their operation,

Fig. 17, is a diagrammatic view showing the relation of the switches with respect to 80 the circuits that are controlled thereby, and

Fig. 18, is a detail view, in perspective, of certain of the tripping mechanism which I employ.

The switch is provided with a cover 18 85 and a base 19. A frame 20 is secured to the base 19 by bolts 21. A bearing 23 is secured to the front of the frame 20 and is perforated to permit the passage therethrough of

a handle shaft 24 that carries a handle 25 90 which may be oscillated between stop members 26 and 27, the stop members consisting of bent-up portions of the frame 20. A rear bearing 28 is secured to the base 19 by up-

setting the lower end at 29 (Fig. 2). The 95 lower end of the shaft 24 is flattened slightly so that the handle bracket 31 may be non-rotatably engaged thereby, by reason of the contour of a hole 32 in the bracket. (See

Fig. 6.) The bracket 31 is of U-shape and is 100

provided with a slot 33 at its middle portion within which a pin 34 may slide horizontally.

The pin 34 is provided with grooves 36 (Fig. 15) that are engaged by the ends of a pair of tension springs 37. The other ends of the springs 37 are supported by a pin 38, the upper and lower ends of which lie in the cut-out portions 39 (Fig. 9) of a carrier 41 for movable contact members 42 (only one of which is shown in Fig. 1) that co-operate with stationary contact members 43 to close the circuit through a starting winding of a motor connected in the circuit.

When the handle 25 is turned in a counter-clockwise direction, the pin 34, by reason of its location in the slot 33 of the handle bracket 31 will also be moved in a counter-clockwise direction and will engage with shoulders 44 (Figs. 1, 9 and 10) of the contact carrier 41, thus moving such contact carrier and the contact members that are carried thereby into engagement with the stationary contact member 43. This effects the closure of what I designate as the starting switch.

A tension spring 49 is supported at one of its ends by the pin 38, in a groove similar to the grooves 36 of the pin 34, and at its other end is supported by a pin 51 whose ends lie in recesses 52 of another movable contact bracket 53 (Figs. 1, 7 and 8) that serves as a support for movable contact members 54 that are moved into and out of engagement with stationary contact members 56 to effect a closure of what is herein designated as the running switch.

When the starting switch bracket 41 and the pin 38 that is supported thereby are turned in a counter-clockwise direction, the spring 49, which is under tension, is carried across the axis of the rotatable members, thereby changing the direction of tension exerted by such spring 49 upon the bracket 53 and causing such bracket to be moved to the position shown in Fig. 16. At this stage of the operation, the running and starting switches are both closed.

As the contact carrying brackets 53 and 41 move in clockwise and counter-clockwise directions, respectively, shouldered portions 57 of the bracket 53 engage the front and rear ends, respectively, of the pin 34, moving it radially out of engagement with the shouldered portion 44 of the bracket 41, thus disengaging such bracket and permitting it to move independently of the handle 25 and the handle bracket 31.

A relatively stiff spring 58 has one of its ends secured at the point 59 to the frame 20 and the other end thereof secured at 61 to the bracket 41 (see Figs. 1, 4 and 9). As the handle is turned to close the starting switch the movement of the bracket 41 increases the tension of the spring 58. Upon the pin 34 being tripped free of the shoulder 44 of the

bracket 41, as above described, the tension of the spring 58 is sufficient to return the bracket 41 to the position shown in Fig. 1, against the tension of the springs 37 and 49. This movement also returns that portion of the spring 49 which is supported by the pin 38 to the position illustrated in Fig. 1.

A locking lever 62 is pivotally supported in the frame 20, by a pin 60, and is normally biased in a clockwise direction by the spring 63 (Figs. 1 and 2). A pin 64 extends through openings 65 in the lever 62 and carries rollers 66 at its front and rear ends. When the bracket 53 has been moved to the position shown in Fig. 16, the roller 66, by reason of the clockwise tension exerted upon the lever 62 will engage a pair of shoulders 67 on the bracket 53 to hold the bracket 53 in closed position (as shown in Fig. 16) against the tension of the spring 49, when the end of that spring which is supported by the pin 38 has been returned to the position shown in Fig. 1, as above explained.

The return movement of the bracket 41, under the tension of the spring 58, places the handle bracket 31 under tension, by reason of the elongation of the springs 37, but the bracket 31 is prevented from moving to "off" position so long as the pin 34 remains in engagement with the shouldered portion 57 of the bracket 53. The position occupied by the handle 25, with respect to the stop lugs 26, and 27, thus indicates that the running switch is closed.

An electromagnet 68 for controlling the starting switch comprises two coils 69 and 70, that may contain unequal ampere turns, and which are connected in the circuit, as shown in Fig. 17, to co-operate with an armature 71 which is carried upon a tail piece 72 of the starting switch bracket 41. The differential in the magnetic forces of the coils excited on the armature 71 is sufficient to hold the starting switch closed when the switches are in the position occupied in Fig. 16.

The effective holding force of the magnet 68 varies, as will be hereinafter explained, but normally holds the starting switch closed against the tension of the spring 58 for a short period. When the magnetism has been sufficiently reduced, as will be hereinafter explained, the tension of the spring 58 will impart an opening movement to the starting switch, as described above.

With the starting switch in the position illustrated in Fig. 1, and the running switch as illustrated in Fig. 16, the motor will operate under normal running conditions and may be stopped either by manually effecting an opening movement of the running switch 125 or by automatically effecting such movement.

The running switch may be opened manually by turning the handle 25 in a clockwise direction, thus bringing the beveled portions 130

73 (Figs. 5 and 6) of the handle bracket 31 into engagement with the rollers 66 to cam them out of engagement with the shouldered portions 67 of the bracket 53. The handle is then held in its "off" position against the stop 26, by the tension of the springs 37, and the running switch bracket 53 is snapped to its open position by the tension of the spring 49.

10 The running switch may be opened automatically upon the occurrence of an overload by the coil 70 that actuates an armature 74 which is pivotally supported upon the pin 60 and is biased outwardly by a 15 spring 63a. An abnormal energization of the coil 70 will attract the armature 74 against the tension of the spring 63a, and move it into engagement with lugs 62a of the lever 62 and causes a counter clockwise 20 movement by the lever 62, thus moving the rollers 66 out of engagement with the shoulders 67 of the running switch bracket and permitting the spring 49 to return the running switch bracket 53 to open position. 25 The opening movement of the bracket 53 causes the release of the pin 34 from its engagement with the shoulders 57 and allows the handle 25 to be returned to its off position, as in the case of the manual operation 30 above described.

As shown more clearly in Fig. 4, the frame 20 is provided with stop portions 76 for engaging the front ends of the pins 38 and 51 to limit their movements, the rear ends of 35 the pins engaging the end walls of arcuate slots 76a in the base 19. The bearings 23 and 28 and the handle shaft 24 are of short length to permit movement of the spring 49 across the axis of the movable parts that are 40 supported thereby, and the bracket members 31, 41 and 53 are of U-shape, to leave a clear space for movement by the springs 37 and 49. Furthermore, this U-shape construction of the bracket members 41 and 53, 45 together with their recesses, which radiate from their central portions (see Figs. 7 and 9) permit the ready assembly or disassembly of these parts, in that such brackets may be inserted into place from the side of the switch 50 by moving them radially into engagement with the grooved portion of the bearing members 23 and 28. The tension exerted by the spring 49, through the pins 38 and 51, serves to hold the recessed central portions 55 of these brackets into close-fitting engagement with the grooved bearing members 23 and 28. The pins 34, 38 and 51 are each grooved adjacent to their ends in substantially the manner indicated in Fig. 15, so that 60 such end grooves will engage their respective associated brackets to prevent vertical movement by the pins.

Referring now more particularly to Fig. 17, a main circuit 77 is controlled by the 65 running switch 79. The running switch 79

primarily controls the supply of current to a starting winding 81 of a motor a running winding 82 thereof, but only indirectly controls the flow of current to the former winding. When the running switch 79 is closed, 70 it completes the circuit through the coil 70 and the winding 82. When starting, the switch 42 is also closed, and the circuit through the starting winding 81 is complete.

Upon the closure of both the starting 75 switch and the running switch, current is supplied to both windings 81 and 82. The differential magnetism of the coils 69 and 70 is then sufficient to maintain the armatures 71 in the position illustrated in Fig. 16, and a 80 high temperature-coefficient resistance 84 is provided in the shunt circuit 78. After current has been directed through the shunt circuit and coil 69 for a short time, the resistance offered by the element 84 increases 85 by reason of the heating thereof, and causes more current to flow through coil 70, thus reducing the holding force exerted by the magnet 68 and permitting the spring 58 to move the starting switch 42 (bracket 41) 90 to open position, as above described. The starting switch will, therefore, not be held closed for a period sufficient to cause injury to the motor that the apparatus is designed 95 to control.

Fig. 18 shows, in detail, the relation of the coils 69 and 70 to the armatures 71 and 74. When the starting switch is closed and the armature 71 moved to the position shown in Fig. 16, the running switch is caused to close 100 as above explained. The circuit through the coils 69 and 70 is then complete, causing the armature 71 to be retained in the said position until the resistance 84 becomes heated and the flow of current therethrough reduced. 105 This causes an increased flow of current through the coil 70.

The flow of current through the coil 69 being reduced and that through coil 70 increased, and the coils being energized in opposite directions, the differential therebetween that creates a magnetic flux through the core during starting, is reduced a sufficient amount to permit the spring 58 to open the starting switch against the magnetic 110 force exerted upon the armature 71. The circuit through the coil 69 and the starting winding 81 is then broken, leaving only the coil 70 effective. The coil 70, being in series with the main winding 82, then acts as an ordinary overload coil and, owing to the remote position then occupied by the armature 71, any magnetic force set up around the core 86 will be exerted mainly upon the armature 74 against the tension of a spring 63a, thus moving the armature 74 against the latch lever 62a and the tension of the spring 63 to free the running switch (running switch 79—bracket 53) from the lever 62 and permitting the switch to be moved to open posi- 115 120 125 130

tion by the tension spring 49, as above described.

I have, therefore, provided means for insuring that the running switch shall not be maintained in closed position so long as an overload obtains on the circuit.

While the device has been described in its application to an alternating current motor, of the induction type, it may be employed in connection with various other classes of apparatus wherein primary and secondary circuit conditions exist.

I claim as my invention:

1. The combination with a starting switch and a running switch, of a handle for manually closing the starting switch, a tension connection between the starting switch and the running switch for biasing the running switch toward the position occupied by the starting switch, means for disengaging the starting switch from the handle when such switch is closed, means for automatically returning the starting switch to open position, means controlled by the running switch for maintaining the handle in its closed position during the time that the said switch is closed, and a tension connection between the starting switch and the handle for returning the handle to its off position when it has been disengaged from the running switch.

2. The combination with a starting switch and a running switch, of a handle for directly actuating the said switches, means for moving the starting switch to open position independently of the handle and the running switch, and means for returning the handle to its open position when the running switch is opened.

3. The combination with a starting switch and a running switch, of a common mechanical means for closing the said switches, means for opening the starting switch independently of the said closing means, and means for opening the running switch whenever the said closing means is returned to open position.

4. The combination with a starting switch and a running switch, of a handle for closing the said switches, means for moving the starting switch to open position independently of the handle and the running switch, means for retaining the handle in its closed position while the running switch remains closed, means for automatically opening the running switch, and means for returning the handle to its open position whenever the running switch is opened.

5. The combination with a starting switch and a running switch, of a handle for closing the said switches, means for opening the starting switch independently of the said closing means and means so associated with the running switch and a handle that the handle indicates, through its associated

movement, the position of the running switch.

In testimony whereof, I have hereunto subscribed my name this 13th day of May, 1926.

HUBERT K. KRANTZ.
